UNITED STATES PATENT OFFICE.

FRANK SCHNEIBLE, OF NEW YORK, N. Y., ASSIGNOR TO C. A. SCHNEIBLE, INC., OF NEW YORK, N. Y., A CORPORATION OF NEW YORK.

APPARATUS FOR DISPENSING LIQUIDS.

1,184,031.

Specification of Letters Patent.

Patented May 23, 1916.

Application filed January 2, 1915. Serial No. 39.

To all whom it may concern:

Be it known that I, FRANK SCHNEIBLE, a citizen of the United States, residing in the borough of Manhattan of the city of New York, in the State of New York, have invented certain new and useful Improvements in Apparatus for Dispensing Liquids, of which the following is a specification, reference being had to the accompanying 10 drawings, forming a part hereof.

This invention relates to apparatus for dispensing liquids and is concerned particularly with a system by which variable quantities of a liquid may be drawn off under the control of a single member, or whereby two or more dissimilar liquids may be drawn off simultaneously into a common receptacle by manipulation of the said actuating member, the invention when used for 15 the serving of dissimilar liquids also permitting the relative proportions of the various liquids to be fixed.

The invention, as illustrated, indicates two embodiments thereof, in one of which 20 it is possible to draw off three different combinations of the liquid or liquids to be served, while the other shows a far greater number of possible positions for the controlling member and accordingly permits a 25 greater number of combinations, either in volume or composition.

In accordance with the invention there are provided two or more containers for the liquid or liquids to be discharged, which 30 containers may or may not be of different capacities, and a controlling valve for each of such containers, the stem of each valve being extended beyond the valve casing and susceptible of operative engagement by a 35 controlling member arranged to be manipulated manually. Each valve stem is so constructed that the said controlling member or handle will engage it operatively when in certain positions with respect to the stem 40 but will not engage the stem operatively when in certain other positions. By placing the controlling member in predetermined positions with respect to the stems of the several valves, one or more of these 45 valves can be operated to bring about the discharge of either a predetermined quantity of a liquid, or a measured quantity of a liquid of predetermined composition. By shifting the controlling member to other positions with respect to the stems of the 50

valves different quantities of liquid or different quantities of liquids of different composition, can be dispensed.

The invention is not only concerned broadly with a dispensing system of the 60 character outlined above, but also relates to certain improved devices by which these desired results are secured such as, for example, the containers for the liquid and a common discharge nozzle with which all of 65 the pipes of the system communicate.

The invention will be described more particularly with reference to the accompanying drawings, in which—

Figure 1 is a view, partly in front elevation and partly in vertical section, of a system embodying the present invention, the showing being somewhat diagrammatic and the relative perspective of the elements being disregarded in the interest of clearness. 70 Fig. 2 is a fragmentary view on a larger scale, partly in plan and partly in section, of a modified structure in which only two containers are intended to be connected in the system. Fig. 3 is a view, partly in section 80 taken along the plane indicated by the line 3—3 of Fig. 2 and looking in the direction of the arrows and showing particularly the single controlling member for the valves. Fig. 4 is a view, partly in elevation and 85 partly in section, of one of the improved containers to be used in the present apparatus and indicating the controlling valve for the discharge of liquid therefrom. Fig. 5 is a fragmentary view, partly in elevation 90 and partly in section, of one of the containers connected in the improved system and indicating particularly a controlling valve and the controlling handle therefor. Fig. 6 is a fragmentary view, partly in vertical section and partly in elevation, of a portion of one of the valves shown in Fig. 1 and indicating in dotted lines one position 95 of the controlling member for the valve in which the valve is not operated by movement of the member.

As this description proceeds, it will be clear that the apparatus may include any number of containers for liquid of any relative capacities and the number of possible 105 combinations in volume and in composition of the liquid discharged will be limited only by the number of such containers. In the apparatus shown in Fig. 1, for instance, there are four such containers *a*, *b*, *c*, *d*, 110

while in Fig. 2 there are illustrated only two valves e , e' , which will, of course, serve to control only two containers. Where the apparatus is used for dispensing beverages, such as ale, beer, porter, etc., the containers a , b , c , d , will preferably be disposed in an ice chest f into which will lead a supply pipe g for the containers and from which will pass the several discharge pipes a' , b' , c' , d' , leading from the respective containers a , b , c , d , and communicating respectively with valve casings a^2 , b^2 , c^2 , d^2 , the valves of which are controlled in a manner to be pointed out. Each of the containers a , b , c , d is also in communication with the supply pipe g through the respective valve casings a^2 , b^2 , c^2 , d^2 , through other pipes a^3 , b^3 , c^3 , d^3 , respectively.

Since each of the containers is similar in construction to the other containers and the various pipes communicating therewith and with the supply pipe g , and the controlling valves, therefor, are also similar to the corresponding parts associated with the other containers, reference may be had to Fig. 5 for a specific description of one of these containers, such as the container a , and its associated elements. From the supply pipe g the liquid flows through a duct h in a plug valve h' . It is evident that when the port h is in such position as to establish communication between the short branch g' of the supply pipe g , and the pipe a^3 , liquid will flow freely from the supply pipe g into one end of the container a . At the same time, another port h^2 in the valve plug h' lies in such position as to establish communication between the other pipe a' with which the container communicates at its other end, and a discharge pipe i which terminates in the discharge nozzle i' , the structure of which will be later described. When the four-way cock h' is rocked in either direction through a quarter turn, the ports h and h^2 will assume such positions as to establish communication respectively between the pipes a^3 and i and the pipes g' and a' . With the valve h' in this position, a reversal of the flow of the liquid with respect to the container a will be brought about. This reversal of flow permits the container a to be used as a measuring vessel, as will appear more clearly from the detail view shown in Fig. 4. In this figure it appears that a freely slideable, but liquid tight, piston k is disposed transversely of the interior of the container a and this piston separates the container into two separate compartments. When the liquid moves into the container on one side of this piston k the latter will be moved toward the opposite end of the container, thus forcing out the liquid on such opposite side while permitting the container to become filled with liquid from the first named side. When the

cock h' is moved to reverse the positions of the ports h and h^2 therein with respect to the pipes a' , a^3 and i , in the manner hereinbefore indicated, a reversal of inflow and outflow will occur, so that the measured quantity of liquid stored in the container a is discharged to the receiving vessel at the nozzle i' .

It might be well at this time to point out that the container a is of improved construction in that the measured quantities of liquid to be delivered thereby may be varied through a very simple adjustment. Still referring to Fig. 4, it is evident that the piston k seats at one end of the container a on an inwardly projecting portion α^4 of the pipe a' and seats at its other extreme position of travel on the inwardly projecting end of a threaded tube l , the latter being adjustably screwed into the removable end plate a^5 of the container a . The tube l may be locked in any adjusted position by means of a lock nut l' threaded thereon. Further, a convenient way of providing for accessibility to the tube l is found in a threaded cap m adapted to completely inclose the tube l and communicate with the pipe a^3 . The cap m is removably secured on the end plate a^5 of the container a . By removing the cap m and loosening the lock nut l' , it is evident that the tube l may be moved axially to vary the effective range of movement of the piston k along the container a , thereby changing the effective capacity of the container a and the quantity of liquid discharged therefrom upon each movement of the piston in the manner before described.

The dispensing apparatus having now been described the interrelation of the controlling valves for the various containers, whereby variable quantities of liquid or liquids of varying compositions may be dispensed, will now be pointed out. It is with the interrelation of these units that this invention is particularly concerned.

One simple embodiment of the invention is indicated in Fig. 2 wherein it may be supposed that the broken pipes G' communicate with some main supply pipe, corresponding, for instance, to the supply pipe g , referred to in connection with the description of Figs. 1 and 5. The flow of liquid from the short pipes G' to their respective containers, not illustrated, but corresponding to container a , and from these containers to the discharge pipes I (corresponding to the discharge pipe i hereinbefore described), may be controlled by the two valves e and e' , one for each container. These valves e and e' are the usual four-way, plug type and are shown as pressed into their respective valve casings E , E' , by means of spiral springs M seating on removable plugs E^2 threaded into the ends of the respective valve casings. 125

The valves e , e' are reversely disposed with respect to each other and have their respective stems e^2 extended toward each other and in alinement and preferably formed of 5 polygonal outline to permit the cooperation therewith, either singly or together, of a controlling handle n slidably mounted on the alined stems.

Assuming now that the containers controlled respectively by the valves e and e' are 10 of different capacities or contain different liquids, such as ale and porter, or are of different capacities and contain different liquids which are to be discharged into a 15 common vessel, it is evident that the operator may slide the single controlling handle n along the stems e^2 of the valves so as to bring about operation only of the valve e' , or operation only of the other valve e , 20 when in the position indicated in Fig. 2, or operation of the two valves together, thereby causing the dispensing of such liquid as is in the container controlled by the valve e' , or of the liquid in the container controlled 25 by the valve e , or of the liquid contained in the two containers controlled by said valves, according to which of the three positions enumerated above, the handle is placed in.

In Fig. 1 the invention is shown as embodied in an apparatus by which many combinations, as regards quantity, can be obtained. In this embodiment there are four 30 containers a , b , c , d , which are connected to the respective valve casings a^2 , b^2 , c^2 , d^2 , in 35 the manner described with reference to Figs. 4 and 5, and the inflow and outflow of liquid from these various containers are controlled as hereinbefore pointed out. Each of the 40 controlling valves, similar generally in construction to the valve h' shown in Fig. 6, within each of the valve casings a^2 , b^2 , c^2 , d^2 , has its stem extended an appreciable distance beyond the casing, as indicated 45 respectively at h^3 , h^4 , h^5 , h^6 . These several 50 valve stems, or mere spindles (as they may be), are journaled in substantial alinement, each with each, in suitable bearings f' and f^2 carried by the chest f . While these bearings f' and f^2 are not illustrated in detail, 55 they may be of such construction as to permit axial movement of the respective stems therein for the purpose of compensating for 60 wear of parts. Each of the stems h^3 , h^4 , h^5 , h^6 , is formed with alternate depressions and 65 protrusions, or the equivalent, for coöperation in a suitable operating handle N . As shown in Fig. 1, the protrusions are shown in the form of polygonal or square bosses h^7 , h^8 , h^9 , h^{10} , formed respectively on the spindles h^3 , h^4 , h^5 , h^6 , and the protrusions on each of these stems are of equal length considered longitudinally of the stem, but are of a different length from the protrusions on each of the other stems. The depressions or 70 dwell positions for the controlling handle N

are shown in Fig. 1 in the form of cylindrical sections h^{11} , h^{12} , h^{13} , h^{14} , disposed on each stem h^3 , h^4 , h^5 , h^6 , respectively, in alternation with the respective polygonal protrusions h^7 , h^8 , h^9 , h^{10} . One of the containers a , which may be the smallest container where variable quantities of liquid are to be dispensed, may have the spindle h^3 of its controlling valve h' formed with a 75 relatively great number (eight) of polygonal bosses h^7 whereby the contents of that particular container will be dispensed in a relatively great number of the possible positions which the controlling handle N may be given, as will hereinafter appear. Because the container a is smaller than any of the other containers, it is desirable to have its contents dispensed with the contents of the larger containers, a relatively great number of different times, as a relatively fine 80 graduation may thereby be secured. The spindle h^4 of the controlling valve for what may be assumed to be, for the purposes of this description, the next larger container b , may have formed thereon only, say, four 85 polygonal protrusions h^8 . The next container, such as c , may have its controlling spindle h^5 , formed with only two polygonal protrusions h^9 , while the fourth container d , in the illustrated example, may have its controlling spindle h^6 formed with only one 90 such protrusion h^{10} .

In operation, assuming that the smallest possible quantity of liquid, or that a certain kind of liquid within the container a , is to 100 be dispensed, the handle N will be slid by the operator to its extreme position at the left end of the spindles h^3 , h^4 , h^5 , h^6 , as shown in Fig. 1, in which position one branch N' of the handle will engage operatively the 105 end polygonal boss h^7 of the spindle h^3 , while the other three branches N^2 , N^3 , N^4 will rest on a cylindrical or dwell portion of the other valve spindles h^4 , h^5 , h^6 . If the handle N is then rocked, only the valve 110 within the casing a^2 will be moved to permit the flow of liquid from the container controlled thereby, in the supposed case, the container a . If the next larger quantity of liquid or the liquid in the container b , is to 115 be dispensed, the operator will slide the handle N one step to the right (as viewed in Fig. 1) where the branch N^2 will engage operatively the end polygonal boss h^8 of the spindle h^4 , while the remaining three branches N' , N^3 , N^4 will rest on cylindrical or dwell portions of the other stems h^3 , h^5 , h^6 . Operation of the handle N will then cause the valve within the casing b^2 to permit the outflow of liquid from the container b . The next position of the handle N will 120 permit the outflow of the liquid from both the containers a and b , thus giving the next graduated quantity and so on, the valves of the several containers being graduated in 125 130

varying combinations intended always to give either a predetermined quantity of a single liquid or a predetermined quantity of a liquid of known composition.

5 For the convenience of the operator, the handle N may be provided with an index finger N^5 arranged to move along a suitable scale o graduated to indicate either the quantity of the liquid to be withdrawn when the 10 valve handle N is actuated with the pointer N^5 opposite a certain scale division, or the composition of the liquid for such a position, or both. The range of movement of the handle N about the valve spindles may be 15 limited by the operator by means of rods p mounted conveniently on the valve casings and extending longitudinally of the spindles on opposite sides of the handle.

From the description given, it will be appreciated that in an apparatus of this kind 20 designed to discharge liquids of varying characters from a common nozzle, it is important to guard against commingling of the dead liquid in each discharge pipe with 25 the liquid dispensed from the remaining pipes, when only controlling valves for the last named pipes are manipulated. To this end, supplemental check valves for each 30 pipe employed in the improved apparatus are provided in the body of the common discharge nozzle, so that each discharge pipe between the main controlling valve and the supplemental check valve is also controlled. As shown in Fig. 1, the body i^2 of the discharge nozzle i' is arranged with inner passages i^3 , with which communicate the ends of the several discharge pipes i and each of these inlet ducts i^3 is controlled by a check valve q recessed on its inner face, as at q' , 35 and pressed to its seat by a spring r seated on a perforated plate s mounted transversely within the nozzle i_1 . The springs r are of such tension as to hold the respective check valves q in closed position until the main 40 controlling valve within one of the valve casings a^2 , b^2 , c^2 , d^2 , is manipulated to permit flow of liquid through the respective discharge pipes i , whereupon the check valve controlling the pipe through which the 45 liquid is to pass is unseated to permit the outflow of such liquid. Immediately upon the closing of the controlling valve, however, the check valve returns to its seat and prevents drip from the pipe closed thereby.

50 The apparatus illustrated herein is shown and described merely by way of examples of particular embodiments of the improved system, but it is to be understood that the invention is not limited to the number or character of the containers employed, nor to the 55 number of possible variations in quantity or of composition which can be dispensed. Further, the details of the various elements employed in practising the invention in accordance with the shown embodiments, may

be changed by those skilled in the art without losing the benefits of the invention. Accordingly, it is to be understood that all changes and rearrangements and modifications which suggest themselves are to be deemed within the spirit of this invention, provided they fall within the scope of the appended claims.

I claim as my invention:

1. Apparatus for dispensing liquids comprising containers therefor, valves to control the discharge of liquid from the respective containers, and a single integral controlling handle movable to operative relation with one, two or more of said valves and itself movable to actuate the valves and permit the simultaneous discharge of a variable number of containers.

2. In combination with a source of supply of liquid, apparatus for dispensing said liquid in variable measured quantities, comprising containers of predetermined capacities, valves to control the discharge of the liquid from said containers respectively and means to actuate said valves, said means being movable selectively as a unitary structure and by a single manipulation into operative relation with one, two or more of said valves to permit the discharge of variable measured quantities of liquid.

3. In combination with a source of supply of liquid containers communicating with said source of supply, discharge pipes leading from said containers, four-way valves controlling the flow of liquid from the supply to the containers and from the containers through the discharge pipes respectively, and a single integral controlling handle for said valves adjustable to actuate one, two or more of said valves and itself movable to actuate the valves and permit the charge of variable quantities of liquid.

4. Apparatus for dispensing liquid comprising containers of predetermined capacities, valve for controlling the flow of liquid into and from said containers respectively, valve spindles extending beyond the respective valve casings, and a single controlling handle mounted slidably on said spindles whereby simultaneous movement of the valves by a single manipulation can be effected, said spindles being provided with dwell positions at which the handle moves freely with respect to the spindle.

5. In combination with a source of supply of liquid, containers of different capacities communicating therewith, a common discharge nozzle with which all of said containers communicate, four-way valves for said containers respectively to control by a single manipulation the flow of liquid to and from the containers, valve spindles extending beyond the valves respectively and a single controlling handle mounted slidably on said spindles and arranged to engage the

respective spindles operatively in certain positions whereby the valves can be actuated in variable combinations by a single manipulation of the controlling handle.

- 5 6. In combination with a source of supply of liquid, apparatus for dispensing the liquid, comprising containers of different capacities, a common discharge nozzle for the containers, pipes connecting the containers with the source of supply and with the nozzle, valve casings connected in the pipe connections, spring-pressed valves disposed in said casings respectively, spindles for the valves extending beyond the valve casings and mounted in alinement each with 30 each, a single controlling handle mounted slidably on said spindles, sections on each of said spindles in which the handle is operative, the number of such sections on each spindle differing from the number of such 35 section on each of the other spindles whereby graduated combinations of variable quantities of liquid can be dispensed through a single manipulation of the handle, and a graduated scale across which the handle may 40 be moved to indicate to the operator the character of the combination of liquid to be discharged for each position of the handle.
- 10 15 20 25 7. In combination with a source of supply of liquid, apparatus for dispensing the liquid, comprising containers of different capacities, a common discharge nozzle for the containers, pipes connecting the containers with the source of supply and with the nozzle, valve casings connected in the pipe connections, spring-pressed valves disposed in said casings respectively, spindles for the valves extending beyond the valve casings and mounted in alinement each with each, a single controlling handle mounted slidably on said spindles, sections on each of said spindles in which the handle is operative, the number of such sections on each spindle differing from the number of such section on each of the other spindles whereby graduated combinations of variable quantities of liquid can be dispensed through a single manipulation of the handle, and a graduated scale across which the handle may be moved to indicate to the operator the character of the combination of liquid to be discharged for each position of the handle.
- 25 7. In combination with a source of supply of liquid, apparatus for dispensing the liquid, comprising containers of different capacities, a common discharge nozzle for the containers, pipes connecting the containers with the source of supply and with the nozzle, valve casings connected in the pipe connections, spring-pressed valves disposed in said casings respectively, spindles for the valves extending beyond the valve casings and mounted in alinement each with each, a single controlling handle mounted slidably on said spindles, sections on each of said spindles in which the handle is operative, the number of such sections on each spindle differing from the number of such section on each of the other spindles whereby graduated combinations of variable quantities of liquid can be dispensed through a single manipulation of the handle, and a graduated scale across which the handle may be moved to indicate to the operator the character of the combination of liquid to be discharged for each position of the handle.

This specification signed and witnessed this 26th day of December, A. D. 1914.
